UNITED STATES PATENT OFFICE.

CLIO B. YAW, OF ARLINGTON, NEW JERSEY, ASSIGNOR TO REMINGTON TYPEWRITER COMPANY, OF ILLION, NEW YORK, A CORPORATION OF NEW YORK.

TYPE-WRITING MACHINE.

1,250,408.

Specification of Letters Patent. Patented Dec. 18, 1917.

Original application filed September 16, 1914, Serial No. 861,966. Divided and this application filed June 9, 1916. Serial No. 102,643.

To all whom it may concern:

Be it known that I, CLIO B. YAW, a citizen of the United States, and resident of Arlington, in the county of Hudson and State of New Jersey, have invented certain new and useful Improvements in Type-Writing Machines, of which the following is a specification.

My present invention relates to ribbon mechanism and more especially to ribbon mechanism that is suitable for use with tally strip devices. The principal object of my invention is to provide new and improved mechanism of the character specified. The 10 present application is a division of my prior application Serial No. 861,966, filed September 16, 1914.

To the above and other ends my invention consists in the features of construction, combinations of devices and arrangements of parts hereinafter described and particularly pointed out in the claims.

In the accompanying drawings,

Figure 1 is a fragmentary front elevation of the upper portion of a No. 11 Remington typewriting machine embodying the preferred form of my invention.

Fig. 2 is a side elevation of Fig. 1, the line-spacing-handle and connections also being shown.

Fig. 3 is a horizontal sectional view taken on the plane indicated by the dotted line $\alpha-\alpha$ in Fig. 2 and looking downward.

Fig. 4 is a fragmentary sectional view taken longitudinally of the platen through its axis.

Fig. 5 is a fragmentary front elevation of the platen and associate parts showing the construction of the paper feeding devices 40 that coöperate with the platen.

As appears from Figs. 1, 2 and 5 the main frame of the No. 11 Remington front-strike typewriting machine to which my invention is shown as applied, comprises a top plate 1 from which rise lugs 2 that support grooved guide rails 3, said rails coöoperating through anti-friction balls 4 with the front bar 5 and rear bar 6 of a carriage truck which further includes end bars 7 connecting said front and rear bars. Shiftably connected with said truck by devices 8 is a platen frame or carrier comprising end bars or plates 9 and cross rods or bars 10 and 11, said platen frame and its supporting truck

constituting a traveling platen carriage. The ends bars 9 provide bearings for a two-part shaft 13 on which is mounted a rotatory platen 14. As is shown in Fig. 4 the right-hand section of the shaft 13 bears in a bushing 15 threaded into the end bar 9. The 60 platen 14 comprises an ordinary wooden core 16 and rubber sheath 17. At the right-hand end the shaft 13 is secured in a platen head 18 secured to the core by screws 19. The reduced outer end of the head 18 receives a line spacing ratchet wheel 20 secured by screws 21. Confined loosely between the ratchet wheel 20 and the end of the platen is a second line spacing ratchet wheel 22 and a gear wheel 23 pinned together at 24. 70 Coöoperative with the ratchet wheel 20 is a detent 25 and a line spacing pawl 26, said pawl depending from the stud 27 (Figs. 1 and 2) fixed to a supporting arm 28 loosely mounted on the bushing 15, which also provides a support for a regulating arm 29, arms 28 and 29 being confined loosely between the end bar 9 and a nut 30 screwed on the bushing 15 (Fig. 4).

The pawl 26 is actuated by devices comprising a link 31 (Fig. 2), a bell crank 32, fulcrumed at 33 on the carriage truck, a second link 34, a crank arm 35, and a rock shaft 36 carrying said crank arm, said rock shaft extending forward and terminating in 80 a hand piece 37. The rock shaft bears in a housing 38 fixed to the carriage truck and inclosing a restoring spring (not shown). By operating the line-spacing-hand piece or handle 37 the train of devices connecting it 85 with the pawl 26 is actuated causing the pawl to coöperate with the ratchet wheel 20 to turn the platen through a line space distance. Such actuation of the pawl 26 also automatically actuates a supplementary 95 pawl 39 rotatably mounted on the stud 27 to coöperate with the ratchet wheel 22. A wire spring 40 is coiled around the stud 27 and engages with pins 41 and 42 projecting oppositely from said pawls. The tendency 100 of said spring is constantly to throw or hold the pawl 39 forward away from the ratchet wheel 22 and maintain the pin 42 engaged with the end of a slot 43 in the pawl 26. Devices which are brought into operation 105 automatically are provided to move the pawl 39 into operative position, said devices comprising a bar 44 (Figs. 1-3) having inclined

end portions or cams 45, said bar being rigid on a plate 46 having slots 47 which receive screws 48 threaded into the top plate. With the parts positioned as in the drawings the 5 pawl 39 will be inoperative but as the carriage moves leftward said pawl will engage with the right-hand cam 45 and will be forced rearward by said cam against the spring 40 until said pawl is brought into 10 engagement with the rear face of the bar 44 by which it will be maintained in position to operatively engage with its ratchet wheel during further leftward movements of the carriage until under the force of its 15 spring said pawl rides forward over the left-hand cam 45. The bar 44 is so positioned that during the time it is effective to engage said pawl the tally strip herein-after described is opposite the printing point 20 on the platen. After the pawl rides off the left-hand cam it will become ineffective, but during the return movements of the carriage said pawl will again ride up on to the bar 44 by reason of the action of the left-hand 25 cam 45. It will be understood that the pawl 39 will be effective so long as it is in engagement with the bar 44 but that at all other times it will be inoperative so that 30 actuations of the line spacing handle 37 will not affect said pawl 39 in so far as causing any action on the ratchet wheel 22 is concerned.

Cooperative with the under side of the platen are spring-pressed main and secondary feed rollers each comprising sections 35 numbered respectively 49 and 50 which in turn are respectively mounted on rods 51 and 52 supported at their ends on parallel arms 53 which are carried by lever members 40 55 supported on a rod 56 rigid on the platen frame.

The tally strip devices proper are mounted on two parallel rods or bars 69 and 70 secured to the bars 9 (Figs. 1, 2, 3 and 5). 45 The tally strip supporting frame comprises end plates 71 and a cross bar 71^a, said plates having hub portions 72 which fit over the rods 69 and 70 and receive securing screws. The plates 71 provide bearings for a tally 50 strip delivery carrier spool or holder comprising a hub 73, a flange 74 and a pin 75 formed with a depression which co-operates with a spring pin 76 bearing in a housing 77 on the left-hand plate 71. The hub 73 55 is depressed to co-operate with a friction disk 78 having a stem 79 fixed to the right-hand plate 71. The tally strip 80 wound in roll-form on the usual paste-board core is frictionally supported on the hub 73 and its 60 free end is drawn off at the back of the roll, passing downward over the rod or bar 71^a and thence into the control of feeding devices comprising a central roll composed as shown in Figs. 3 and 5 of a core 82 and 65 sheath 83, the core being slidably mounted

on the shaft 84 which passes through the end plates and bears in the end bars 9. The shaft 84 has a groove 85 which is engaged by tongues 82^a bent inward from the core 82. Rotary movements may be communicated to the shaft 84 to turn the feed roller either by hand through the finger button 86 fixed to the right-hand end of the shaft or automatically through connections between said shaft and the gear wheel 23, said connections comprising a pinion 87 having a hub 88 which receives a set screw 89 which fixes the pinion to the shaft. An idler pinion 90 between the pinion 87 and the gear wheel 23 constantly meshes with both, 75 said idler being rotatably mounted on the rod 69 between collars 91 and 92 (Fig. 1). Cooperative with the central pressure roller at its front and rear sides respectively are pressure rollers 94 and 96, the shafts 97 of 80 said rollers bearing in slots 98 in the end plates 71. Springs 99 engage with the shafts to press the feed rollers 94 and 96 into cooperative engagement with the central roller. The tally strip passes down between the center roller and the feed roller, behind the platen and around the same and up at its front side, and thence between the central and front rollers so that said tally strip may be advanced either by turning the 90 finger button 86 or through the action of the pawl 39.

The main work sheet 105 (Fig. 2) is arranged with its right-hand portion overlying the tally strip, it being fed around the 100 platen by the rollers 49 and 50. Said main sheet receives ink-impressions from a ribbon which is controlled by a vibratory carrier 106 (Fig. 2) of ordinary construction. It is desirable that the tally strip also should receive ink-impressions and that accordingly supplementary inking devices for the tally strip of novel character are provided, said devices comprising (Figs. 1, 2 and 3) two supplementary ribbon spools 107 arranged 105 face to face one on each side of each of the end plates 71. Said spools are mounted loosely on a shaft 108 which extends through openings in said plates 71, the spools being adapted to be connected in alternation to 110 said shaft through hand controlled clutch devices. Certain of said clutch devices serve also as bearings for the shaft 108, being interposed between said shaft and the supplementary ribbon spools of which in effect 115 they are a part. At the left outside the end plates 71, a clutch wheel or member 109 is mounted co-axially with the shaft 108, said wheel being provided with crown clutch teeth 110 and having a hub 111 which extends inward or toward the right through an opening in the plate 71 to the right of which plate is mounted the ribbon spool 107, said spool being fitted over the hub 111 and secured thereto by a set screw 111^a. The 120 125 130

construction permits the clutch wheel 109 and the spool 107 to rotate as one, while the plate 71, interposed between them, prevents movement of the clutch member and spool 5 lengthwise of the shaft 108. This shaft bears in the hub 111 which serves as a journal for it. The shaft may turn independently of the wheel 109 and its ribbon spool, which devices on the other hand may also 10 turn independently of the shaft. Coöperative with the wheel 109 is a second clutch wheel 112 provided with crown clutch teeth 113 that are adapted to mesh with the teeth 110. The wheel 112 is suitably fixed to the 15 shaft 108 near its left-hand end and is provided with a hub 112^a formed with two circumferential grooves 114 and 115. Adapted to coöperate with these grooves is a pivoted latch 116 pivoted at 117 to the end of the 20 cross rod 71^a, and provided with a draw spring 118, which tends to force said latch downward about its pivot and maintain it engaged with one or another of the grooves 114 and 115, depending on which is in register therewith. When thus engaged, endwise movement of the shaft 108 is prevented, but when the latch is lifted the shaft 108 may be shifted endwise to bring the clutch wheel 112 into engagement with the clutch wheel 25 109 or to disengage it therefrom, while at the same time causing corresponding changes to take place in the clutch members associated with the right-hand spool 107 and now to be described. To facilitate endwise 30 movement of the shaft it is provided at its ends with detachable knobs or finger pieces 119. A clutch wheel 120 is arranged at the right of the right-hand plate 71 and is provided with clutch teeth 121 and a hub 122 35 which extends inward through the plate 71 and surrounds the shaft 108. The right-hand spool 107 is fitted over the inner end portion of the hub 122 and is fixed thereto by a set screw 123. The shaft 108 and the 40 wheel 120 are relatively rotatable and in order to connect them for simultaneous rotation a clutch device or wheel 124 is fixed to the shaft 108 near its right-hand end and is formed with inwardly projecting clutch teeth 45 125 adapted for coöperation with the teeth 121. The clutch wheels 112 and 124 are so arranged in respect to their associated clutch wheels that only one of said connecting clutch wheels 112 and 124 can be operative at 50 a time. Thus when the wheel 112 is clutching the wheel 109 and so connecting the left-hand ribbon spool to turn with the shaft 108 the wheel 124 is inoperative and the right-hand ribbon spool is consequently loose on 55 the shaft. If the latch or detent device 116 be lifted and the shaft 108 be moved endwise toward the left, the right-hand spool 107 will be clutched to the shaft by the wheel 124, while the left-hand spool will 60 65 be freed by reason of the disconnection of the clutch wheel 112, thus reversing the direction of the ribbon feed. The shaft 108 is a ribbon driving or power shaft which is adapted to be turned automatically or by hand through connections to the shaft 84. 70 Said connections comprise a pinion 126 which, as best appears from Fig. 5, has a 75 80 85 90 95 100 105 110 115 120 125 130 135 138 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945

108 between the ribbon spools. Thus the guide plate is pivotally supported on the ribbon spool shafts. Said guide plate is formed at its side edges just below and forward of the spools with guide slots 139 through which the ribbon passes in its downward course, and at its lower side the guide plate is formed with diagonal guide slots or turning bars 140 over which the ribbon passes and by which it is directed inward at right-angles in a horizontal direction and so as to be opposite the printing line on the platen, this horizontal portion of the ribbon between the turning bars 140 being the printing portion thereof. The guide plate 134 between the turning bars and above the printing portion of the ribbon is cut away, as indicated at 141, leaving a large open space. It will be understood that when the parts are set as in Fig. 1, the left-hand ribbon spool will be turned to wind the ribbon thereon, the ribbon at the same time being drawn off the right-hand spool and the horizontal printing portion of the ribbon advancing toward the left from the right-hand turning bar to the left-hand turning bar. This printing portion of the ribbon is interposed between the work sheet 105 and the tally strip 80 so that when the right-hand side of the main work sheet receives type impressions through the main ribbon controlled by the carrier 106, the tally strip will simultaneously receive imprints through the auxiliary ribbon 130. By reason of the pivotal mounting of the guide plate 134 it may be swung up to carry the auxiliary ribbon away from the platen and leave the front or printing face thereof fully exposed. The upper edge of the plate 134 is beveled or sharpened, as indicated at 142, to provide a severing device for the tally strip which is led upward between the forward feeding roll and the central feeding roll through the space or slot-way formed between the shaft 108 and the back of the upper portion of the plate 134. Leaf springs 143 pivotally secured on the cross rod 71^a outside the plate 71 extend forward and coöperate at their free ends with the outer flanges of the auxiliary ribbon spools, exerting sufficient pressure on said spools to prevent undue turning movements thereof, said leaf springs thus serving as brakes.

With the parts constructed and arranged as described, when the tally strip is at the right of the printing point the main sheet only will receive type impressions, and an actuation of the line space handle will serve only to advance the main sheet, the tally strip and auxiliary or carriage carried ribbon feeding devices remaining unaffected. When, however, in the course of the leftward movement of the carriage the tally strip is brought opposite the printing point, an actuation of the usual print-

ing instrumentalities will cause type impressions to be made on the main sheet and duplicated on the tally strip, and when thereafter the line spacing handle 37 is operated, it will not only advance the main sheet a unit of line space distance but will automatically advance the tally strip to the same extent and will simultaneously cause a feeding movement of the auxiliary ribbon. 70

Various changes may be made without departing from my invention. 75

What I claim as new and desire to secure by Letters Patent, is:—

1. In a typewriting machine, the combination of a carriage, a platen provided with a work sheet, line spacing mechanism for advancing said work sheet, ribbon mechanism, and means rendered operative by traveling movements of the carriage for bringing said ribbon mechanism into control of said line spacing mechanism. 80 85

2. In a typewriting machine, the combination of a carriage, a platen provided with a work sheet, ribbon mechanism for said work sheet, separate hand controlled actuating devices for said mechanism, and means brought into play during the carriage travel to render said devices effective on said ribbon mechanism. 90

3. In a typewriting machine, the combination of a carriage, a platen thereon, ribbon mechanism carried by said carriage, separate hand actuated devices for said ribbon mechanism, and means brought into play by traveling movements of said carriage for rendering said devices effective on said ribbon mechanism. 95 100

4. In a typewriting machine, the combination of a carriage, a carriage carried ribbon, means for advancing the same comprising a finger piece or key ineffective in certain positions of said carriage; and stationary means for rendering said finger piece effective, said means operating during traveling movements of the carriage. 110

5. In a typewriting machine, the combination of a platen, carriage carried ribbon, pawl and ratchet devices for turning said platen, pawl and ratchet devices for feeding said ribbon, a single finger piece for actuating both sets of pawl and ratchet devices, and means for automatically withdrawing one of said sets of devices from the control of said finger piece and for returning said set to the control of said finger piece. 115 120

6. In a typewriting machine, the combination of a platen, carriage carried ribbon, pawl and ratchet devices for turning said platen, pawl and ratchet devices for feeding said ribbon, and a single finger piece for actuating both sets of pawl and ratchet devices, said finger piece being inoperative to feed the ribbon when the platen is in certain positions. 125

7. In a typewriting machine, the combi- 130

- nation of a carriage, a platen, carriage carried ribbon, ribbon mechanism, line spacing devices controlled by a single finger piece operative to turn the platen and feed the 5 ribbon, connections between said ribbon mechanism and said finger piece including a shaft provided with a finger button, said shaft being movable endwise to break the connections between said mechanism and 10 said finger piece, and said ribbon mechanism then being operative by said finger button independently of said line spacing devices.
8. In a typewriting machine, the combination of a carriage; a platen; carriage carried ribbon spools; a shaft on which said 15 spools are loosely mounted; clutch devices fixedly connected with said ribbon spools; other clutch devices fixedly connected with said shaft, said shaft being movable endwise to render alternately operative the 20 clutch devices thereon; pawl and ratchet devices; and a train of gearing connecting said pawl and ratchet devices with said shaft, said train comprising a gear wheel fixed to 25 said shaft, and a pinion slideable during ribbon reversing operations, said pinion remaining constantly in mesh with said gear wheel.
9. In a typewriting machine, the combination of a carriage, a platen, carriage carried ribbon spools, a shaft on which said 30 spools are loosely mounted, clutch devices, said shaft being movable endwise to alternately connect it with said spools through 35 said clutch devices, and a train of hand ac-
- tuated gearing for turning said shaft, certain members of said train having an unvarying endwise relationship with said platen and certain other members being shiftable endwise of said platen when said 40 shaft is shifted.
10. In a typewriting machine, the combination of ribbon spools, ribbon feeding mechanism, and a ribbon guiding plate arranged to guide the ribbon between said 45 spools, said plate also operating as a paper severing device.
11. In a typewriting machine, the combination of a carriage, carriage carried ribbon spools, ribbon feeding mechanism, and a 50 ribbon guiding plate pivotally supported on said carriage and provided with a paper cutting edge.
12. In a typewriting machine, the combination of a carriage, parallel ribbon spools 55 supported on said carriage, ribbon feeding mechanism, and a guide plate pivotally supported between said spools and provided at its sides with turning bars, the upper edge of said guide plate being beveled to provide 60 a paper severing device.

Signed at the borough of Manhattan, city of New York, in the county of New York, and State of New York this 8th day of June, A. D. 1916.
